(57) **CLAIM**

The ornamental design for a table tennis robot, as shown and described.

DESCRIPTION

FIG. 1 is a front elevational view of the table tennis robot showing our new design;

FIG. 2 is rear elevational view of the table tennis robot showing my new design;

FIG. 3 is the right side elevational view thereof;

FIG. 4 is the left side elevational view thereof;

FIG. 5 is a top plan view thereof; and,

FIG. 6 is a bottom plan view thereof.

All broken lines are for illustrative purposes only, and form no part of the claimed design.
